UNITED STATES PATENT OFFICE

ROBERT LEE MCCOURBIE, OF PHILADELPHIA, PENNSYLVANIA

BOX FASTENING

Application filed April 13, 1928. Serial No. 269,783.

My said invention relates to improvements in fastening means designed more especially for cigar box lids and to take the place of the nail which is customarily used for this 5 purpose.

The invention aims to provide a simple and economical form of fastening which can be easily and quickly applied and which will securely hold the lid in closed position 10 and which will avoid the liability of splitting the wood which frequently occurs with the customary nail type of fastening.

The invention includes the novel construction hereinafter described, the said invention being defined by the appended claims. 15

An embodiment of the invention is illustrated in the accompanying drawing in which:

Figure 1 is a perspective view of a box 20 with the lid in closed position and so held by my improved fastening means.

Fig. 2 is a fragmentary detail showing a portion of the lid and box before the parts are brought together.

Fig. 3 is a fragmentary sectional view 25 showing the block in fastening position, and

Fig. 4 is a perspective view of the block.

Referring by reference characters to this drawing, the numeral 1 designates a wooden 30 box such as the ordinary cigar box, and 2 the lid thereof. In embodying my improved fastening means therein I proceed as follows: With the lid in closed position I proceed to cut a diagonal groove 3 in the upper portion of the front wall (preferably at the center when but one fastener is used) as shown in Fig. 2, which groove intersects or 35 passes through the cover, the bottom of the groove intersecting the inner top edge of the front wall, this forming in the said front wall and juxtaposed cover portion, a groove of triangular shape. This groove may be readily formed by the use of an ordinary saw. 3^a designates a fastener block of suitable material, of triangular shape, its shape 40 and dimensions being such that it will fit exactly and snugly in the aforesaid groove. In applying the fastener it is preferable to insert its larger end in the recess or groove 45 in the edge of the lid as shown at 2^a, in Fig.

2, and secure it therein by glue or similar adhesive with its tapered portion projecting from the lower face of the lid, this being desirably done at the time of manufacture of the box. When it is desired to close and 55 fasten the lid all that is necessary is to apply glue or other adhesive to the sides and back of the projecting portion of the block, or to the walls of the recess or groove in the front wall of the box and then close the lid, 60 which will cause said projecting portion to enter said groove in the box wall and be held therein by the adhesive.

It will be noticed that by reason of the shape of the block and the depth of the cut 65 the fastening block lies wholly within the box wall and cover and there is no projection either within or without the box.

When it is desired to open the box all that is necessary is to insert a knife blade or like 70 instrument beneath the lid and pry it up in the same manner as in opening the nail fastened box which ruptures the glue joint between either the block and cover or block and box wall, usually the former, due to less 75 glue area.

This leaves the fastener block attached to one of the parts and enables the refastening of the box by softening the glue or a fresh glue application. 80

If refastening is not desired, the projecting portion of the block may be trimmed off with a knife if desired.

I have found leather a very suitable material for the fastener block as it is easily 85 cut and, if not of a thickness corresponding exactly to the groove may be spread by a suitable tool (after insertion) to fill the groove, or if slightly thicker than the width of the groove can be compressed for insertion. Another advantage of using leather is that it will give way when the box is opened, before the wood, and prevent breakage of the box. 90

Instead of applying the fastener blocks as above described they may be previously coated with glue or other adhesion which is allowed to dry, and can then be moistened to soften the glue just prior to use and the 100

blocks inserted in the groove when the lid is closed.

Having thus described my invention, what I claim is:

1. In combination, a box having a hinged lid, there being an inclined groove in the outer face of the front wall of the box and edge of the lid, and a tapered filler block filling said groove and adhesively held therein.

10 2. The combination of claim 1 in which the filler block is of leather.

3. In combination, a box having a lid hinged to its back wall, said box having an inclined groove in its front wall, and a tapered projection carried by said lid at its free edge and adapted to enter said groove when the lid is closed and be adhesively secured therein.

20 In testimony whereof I affix my signature.
ROBERT LEE McCOURBRIE.
